UNITED STATES PATENT OFFICE.

GEORGE BUECKLE, OF BROOKLYN, NEW YORK.

THERAPEUTIC APPARATUS.

Application filed December 14, 1920, Serial No. 430,600. Renewed June 14, 1923.

To all whom it may concern:

Be it known that I, GEORGE BUECKLE, a citizen of the United States, and a resident of the city of New York, borough of Brooklyn, in the county of Kings and State of New York, have invented a new and Improved Therapeutic Apparatus, of which the following is a full, clear, and exact description.

10 This invention relates to therapeutic bathing apparatus of the type in which an electric current is caused to circulate through a bathing fluid contained in a tub in which the treatment is administered.

15 An object of the invention is to provide a simple and efficient means whereby the flow of current through the liquid in the tub may be controlled at the will of the operator and with a minimum expenditure of time on the part of the operator in so controlling the flow of current, whereby the distraction of his attention from the patient is reduced to a minimum.

20 A further object resides in the provision of the particular switching arrangement whereby with a minimum number of manipulations any operator can procure the desired flow of current.

25 A further object resides in the provision of a switching arrangement and connection between the same and the tub whereby a much wider range of selection in the flow of current can be obtained, thereby rendering more efficient the physical treatment resulting in the selective application of current to the body of the patient.

30 A still further object resides in the particular construction and arrangement of parts hereinafter described and claimed and shown in the accompanying drawings.

35 In devices hitherto used for the electrical treatment of patients, wherein a tub having a plurality of electrodes disposed therein in any desired manner is used in connection with a bathing fluid, there have been used complicated electrical connecting devices whereby the application of potential and the direction of flow of the current from one electrode to another could be controlled.

40 These devices have, however, necessitated the disconnection of plugs from sockets and the manipulation of a large number of devices whereby considerable attention and expenditure of time on the part of the operator was required to achieve the desired current flow. This demand on the time of the operator not only was a waste of time but distracted his attention from the patient. Furthermore, with such a plurality of operations required to obtain the desired current flow, an operator was forced to be particularly familiar with the apparatus and, therefore, but every operator could manipulate the device. Also, in devices hitherto used, it has not been possible to direct the current flow in any conceivable direction between the electrodes in the tub. Since in the treatment of some forms of ailments it is absolutely necessary to achieve certain hitherto unattainable directions of flow of the current, the achievement of this current flow in accordance with my invention by the use of a simple and easily manipulated device is a marked and distinct advantage over devices hitherto used.

45 Furthermore, the character of my current controlling means is such that it can be mounted on and within the usual panelboard which can be enclosed from view when not in use. My apparatus does not require the use of unsealed plugs and socket connections, and all wires in the system can be covered and hidden from view, thus eliminating the possibility of breaking the wires where such wires are exposed and in constant use.

50 The invention is illustrated in the drawings, of which—

Figure 1 is a diagrammatic view of the entire installation;

Figure 2 is a diagrammatic view of the switchboard;

Figure 3 is a detail view of the switch;

Figure 4 is a perspective view of the tub showing the electrode disposed therein.

As shown in the drawings, with special reference to Figure 1, in the application and operation of my invention I employ a tub 1 which may be of any suitable material, such as slate or other non-conducting, watertight material. On the inner faces of the walls of this tub are disposed a plurality of electrodes 2. These electrodes are disposed vertically in grooves 3 formed in the walls of the tub and are arranged in pairs one above the other in each groove. The electrical current flow between the electrodes of each pair is effected by the contact between abutting edges. These electrodes are arranged, as shown in Figure 4, in pairs, three pairs on each side and two pairs at each end of the tub. The pairs of electrodes at the

end 4 of the tub are called the head electrodes, whereas the electrodes at the opposite end 5 of the tub are called the foot electrodes. The electrodes arranged in the side 5 walls of the tub are, considering them in order from the head 4 to the foot 5 of the tub, called upper, center and lower electrodes. The electrodes 2 are removable from the grooves 3 and can be interchanged at 10 will among the various grooves and with respect to the various electrodes. This interchangeability permits the electrodes to be cleaned frequently, whereby the sanitary condition of the apparatus is maintained to 15 a high degree.

For instance, the pairs of electrodes 6 and 7 are the head electrodes, whereas the pairs of electrodes 8 and 9 are the foot electrodes. Consequently, the pairs of electrodes 10 and 20 11 are the upper electrodes; the pairs of electrodes 12 and 13, the center electrodes; and the pairs of electrodes 14 and 15, the lower electrodes. Each of these electrodes is arranged in the groove 3 in such a manner 25 that it can be slidably moved into and out of the groove. The tub is provided with a slot 16 peripherally arranged on its outer face and in which the wires leading to the various electrodes from the switching apparatus are embedded and covered by any suitable insulating cement. Each of these wires, of course, is insulated from the others and is tapped out at suitable intervals to connect it with its proper electrodes. In Figure 4, 30 cables 17 and 18 are shown, each having five wires therein, the cables 17 connecting with the electrodes one side of the tub including a foot and head electrode, and the cable 18 connecting with the electrodes on the other 40 side of the metal lining of the tub. A plurality of flue pipes 19, 20 and 21 are provided with faucets, such as 22, through which any suitable fluid may be introduced into the tub.

For the purpose of supplying the current 45 necessary to the operation of the invention, any suitable source of current may be used; that shown in the drawings, in Fig. 1, preferably being a direct-current dynamo 23 connected by wires 24 and 25 to a main 50 switch 26 which is preferably an ordinary cut-out or knife switch mounted on a panel board 27. Mounted on the switchboard 27 is a resistance controller 28 of any suitable type which is connected by wire 29 to one 55 side of the switch 26 and by a wire 30 to one of the middle points of a double-throw reversing switch 31. The other middle point of this double-throw switch 31 is connected by a wire 32 to the other side of the switch 60 26. By means of the resistance controller 28 I can control the value of the current flowing to the electrodes in the tub 1. A volt 65 meter 33 is connected in the usual manner across the wires 30 and 32.

Arranged on the switchboard 27 are two

series or sets of opposing contact buttons, certain of which are electrically connected with the electrodes in the tub 1 while others of said buttons are dead, either by being insulated or by being disconnected from the 70 rest of the apparatus in any suitable manner. The two series of contact buttons are alike except that they lead to electrodes on different sides of the tub which may be deemed to be centrally divided through its length by 75 an imaginary line passing therethrough.

Inasmuch as the series of buttons on both sides of the switchboard are alike, a description of one series will suffice for both. These contact buttons are preferably arranged in 80 the arc of a circle and are numbered from 40 to 54 on the left-hand side of the switchboard, and from 40' to 54' on the right-hand side of the switchboard 27. It will be noted that from 40 to 50 the alternate contacts are 85 dead or insulated, that is to say, contact 40 is insulated while contact 41 is a live contact; 42 is insulated and 43 is a live contact, and so on down to contact 50, which is insulated. Contacts 51 to 53 are all live contacts, 90 while contact 54 is insulated. As above stated the live contacts are connected to the electrodes in the bathtub, contact 41 being connected by a wire 55 to the head electrode 6; contact 43 being connected by a wire 56 to the left-hand upper electrode 10; contact 45 being connected by a wire 57 with the left-hand center electrode 12; contact 47 being connected by wire 58 to the lower left-hand 95 electrode 14; contact 49 being connected by a wire 59 to the left-hand foot electrode 8; and contacts 51, 52 and 53 being connected respectively by wires 60, 61 and 62 with contacts 43, 45 and 47 respectively. The contact buttons on the right-hand side of the 100 switchboard, which are denoted by numbers similar to those on the left with the addition of a prime after each number, are connected in an identically similar manner with the electrodes 7, 11, 13, 15 105 and 9 on the right-hand side of the tub 1 shown in Figure 1. The interconnections of these contact buttons are identically similar to the connections above described with reference to the buttons on the left-hand side of the switchboard. For this reason any detail description of the buttons on the right-hand side of the board is not made. The buttons 51 to 53 and 51' to 53' may be termed 110 auxiliary contact buttons for convenience of description since they are interconnected with certain other contact buttons above described.

Pivotedly mounted at opposite sides of the switchboard are the switch arms 63 and 63', the former being mounted on a conducting stud 64, the latter, on a conducting stud 64'. The switch arm 63 is connected by a wire 65 to one side of the switch 31, whereas the switch arm 63' is connected by a wire 65' to 130

the other side of the switch 31. Since the switch 31 is a double pole reversing switch, moving it in one direction or the other will apply opposite polarities to the switch arms 63 and 63', in accordance with the position of the switch 31. Each of these switch arms 63 and 63' is capable of being moved over the entire series of contacts in which they are related. The detail construction of these 10 switch arms is best shown in Figure 3, from which it will be noted that each arm is constructed in the form of a fork having three tines 66. A button or handle portion 67 is disposed on each of the arms to facilitate the 15 movement of the switch arm over the contact button. The tines 66 are spaced apart but electrically and mechanically connected together and so spaced that they extend over an arc equal to the distance between three 20 of the contact buttons.

It will be noted that in Figures 1 and 2 certain of the contact buttons of each set are given a name, such as "head", "upper", "center", "lower" and "foot", corresponding to 25 the electrodes in the tub 1 but which are electrically connected.

In treating a patient by means of the apparatus above described, the cataphoric action of the current is made use of, and it is 30 desired that the current shall pass in a direction or directions calculated to give the greatest efficiency for the purpose of attaining the object in view. Ordinarily it is desired that the current shall pass from one side of the 35 tub to the other, through the patient's body, the point on one side of the tub from which the current passes not necessarily being exactly opposite the point on the other side of the tub to which the current is directed.

40 In other words, the desired action may be along a diagonal line or in a varyingly eccentric line, all of which can be accomplished by my invention.

45 As the connections and positions of the switching devices are shown in Figure 1, it is desired that a positive current of electricity should pass through the patient's body from the right-hand lower side of the body to the upper left-hand side of the head, the heavy 50 dotted line 68 in the drawing of the tub in Figure 1 indicating approximately the direction of the desired current flow. It will be noted, at the switchboard 27, that the switch arm 63 has its central tine connecting with 55 the head contact 41, while the other tines are connected to the insulated contact buttons 40 and 42. On the other side the switch arm 63' has its central tine contacting with the lower contact button 47', the other tines of 60 this arm being connected to the insulated contact buttons 46' and 48'. The circuit through the apparatus for this position of the switch arms 63 and 63' would be as follows: Through dynamo 23, positive side, to 65 wire 25, switch 26, wire 29, resistance con-

troller 28, wire 30, switch 31, wire 65', switch arm 63', contact button 47', wire 58' to electrode 15, through the fluid in the tub, along the diagonal line represented by the numeral 68 to head electrode 6, wire 55 to head contact button 41, switch arm 63, wire 65 to the other side of switch 31, back through wire 32 to switch 26, wire 24, to the other side of the dynamo 23. By suitably adjusting the switch arms at the opposite sides of the 70 switchboard, it will be obvious that current may be caused to pass through the bathtub from one side to the other, the general direction of the current being defined by a line which may be inclined at practically any 75 angle. For example, if it is desired to have the current pass from the central left-hand electrode to the head right-hand electrode 7, the switch arm 63 would be moved so that its middle tine would rest on the contact button 80 85 45, while the switch arm 63' would be moved so that its middle tine rested on the contact button 41'. It is thought that the circuits thus closed are obvious without further detail description thereof. Therefore, the current will flow from any electrode on the right-hand side of the tub to any electrode on the left-hand side of the tub, in accordance with the position of the switch arms 85 90 95 63 and 63'. If the position of switch 31 is reversed, of course, the current will then flow from the left-hand side of the tub to the right-hand side of the tub by reason of the change in polarity effected in this manner.

Owing to the fact that in the main series of contact buttons each alternate button is insulated, only one tine 66 of the forks of the switch arm will contact with a live button in any given position, the middle tine being the one to contact with a live button, while the other two tines will contact with insulated buttons.

With reference to the series of auxiliary contact buttons 50 to 54 above mentioned, it 110 will be noted that the three live buttons 51, 52 and 53 are placed adjacent each other on each side of the switchboard. The object of these auxiliary buttons is to enable the circuit to pass through any given number of 115 electrodes at one side of the tub to any given number on the opposite side of the tub. If, for example, the switch arm 63 is moved so that its three tines rest on the contact buttons 51, 52 and 53, and the switch arm 63' is 120 moved over its contact so that one tine only of arm 63' rests on contact button 51, then the current would flow fan-shaped, passing from electrodes 10, 12 and 14 to the electrode 11.

If it be desired to have current pass through the entire body of the patient, then both switch arms 63 and 63' are moved to their lower position in which the three tines of each fork will rest on the three live con- 125 130

taet buttons of the auxiliary series. There will then be a flow of current from the three electrodes on one side of the tub to the three electrodes on the other side of the tub.

5. An observation of this operation will result in the conclusion that almost any number of combinations of current flow can be achieved by this arrangement, and the foregoing examples have simply been given as 10 illustrative of the possibilities of the device.

The pole changing device or reversing switch 31 is employed in the treatment of certain physical ailments, if desirable, with a positive current entering the body; while in the 15 treatment of other ailments, better results have been obtained if the current entering the body is negative.

In Figure 1, the series of dotted lines shown in the bathtub are illustrative of a 20 number of different combinations of current courses which may be obtained by a suitable adjustment of the respective switch arms on the contact button. It will be obvious that the range of work might, if desired, be extended by the addition of electrodes to the 25 tub and the corresponding addition of contact buttons to the series shown in the drawings.

A consideration of the above-mentioned 30 description of the structure and operation of the apparatus involved in my invention gives rise to the perception that this device is entirely devoid of any cumbersome plug or socket connections; that all wires in the 35 system are properly disposed in positions where the likelihood of breakage is reduced to a minimum; that the operating apparatus on the switchboard is properly enclosed except when in use, taking up a minimum 40 amount of space; that the operator can, by the simple adjustment of a pair of switch arms on the board, selectively direct the current through the tub in a great number of directions; and that the manipulation of 45 these switches require on his part the expenditure of a minimum amount of time and knowledge of the apparatus, so that substantially his entire attention can be given to the patient.

50 It will, of course, be understood that many minor modifications can be made in the structure and in the application of the apparatus shown without departing from the spirit of the invention.

55 What I claim is:

1. A controlling device for therapeutic apparatus having a plurality of electrodes, which comprises a panelboard, a plurality of contacts disposed on the panelboard and 60 connected with the electrodes, the successive contacts so connected being separated by insulating contacts, a switch arm, and a source of power, said switch arm adapted to be moved selectively to energize the various

contacts but the width of the switch arm 65 being insufficient to span the space between successive live contacts.

2. A controlling device for therapeutic apparatus having a plurality of electrodes, which comprises a panelboard, a rotatable 70 switch arm on said board, a source of power connected to said switch arm, and a plurality of contacts connected to the electrodes and disposed in the path of movement of the switch arm, certain of the contacts disposed 75 along one portion of the path of movement of the switch arm being spaced apart but separated by insulated contacts whereby in this portion of the movement of the switch arm the arm can make contact only with one 80 live contact at a time, the contacts along another portion of the path of movement of the switch arm being disposed adjacent each other but permitting the energization of more than one contact at a time by the engagement 85 therewith of the switch arm.

3. A controlling device for therapeutic apparatus having a plurality of electrodes, which comprises a switch arm, a source of power connected thereto, and a plurality of 90 contacts connected to the electrodes and disposed in the path of movement of the switch arm, certain of the contacts along one portion of the path of movement of the switch arm being disposed a sufficient distance 95 apart to prevent energization of more than one contact at one time by the arm, certain of the contacts along another portion of the path of movement of the switch arm being spaced apart a distance sufficient to permit 100 the energization by the switch arm of more than one of the contacts at a time.

4. A controlling device for therapeutic apparatus having a plurality of electrodes arranged in sets, which comprises a panelboard, a plurality of sets of contacts thereon connected to respective sets of electrodes, a switch arm for each set of contacts, and circuit connections between the switch arms, the contacts and the electrodes permitting 105 the energization of the electrodes singly for certain positions of the switch arm and in groups for other positions of the switch arm.

5. A controlling device for therapeutic 115 apparatus, comprising in combination a tub having a plurality of sets of electrodes therein, a plurality of sets of contacts connected respectively to the sets of electrodes, a power source, a switch arm connected thereto, and 120 circuit connections between the switch arm, the electrodes and the contacts whereby the electrodes may be selectively energized singly and in groups at the will of the operator merely by the movement of any switch arm 125 to the desired position.
